CLAIM

We claim the ornamental design for a pencil sharpener, as shown and described.

DESCRIPTION

FIG. 1 is a perspective view of a pencil sharpener according to our new design;

FIG. 2 is a second perspective view of the pencil sharpener of FIG. 1;

FIG. 3 is a front elevational view of the pencil sharpener of FIG. 1;

FIG. 4 is a rear elevational view of the pencil sharpener of FIG. 1;

FIG. 5 is a right side elevational view of the pencil sharpener of FIG. 1; and,

FIG. 6 is a left side elevational view of the pencil sharpener of FIG. 1.

The broken lines showing features on the front and rear in FIGS. 1-4 are included for the purpose of illustrating environment and form no part of the claimed design.
